US0D1059578S

(12) **United States Design Patent** (10) **Patent No.:** **US D1,059,578 S**
(45) **Date of Patent:** **** Jan. 28, 2025**

(54) **CEILING FAN BLADE**

(71) Applicant: **AIR COOL INDUSTRIAL CO., LTD.**, Taichung (TW)

(72) Inventor: **Mark Pickett**, Altadena, CA (US)

(73) Assignee: **AIR COOL INDUSTRIAL CO., LTD.**, Taichung (TW)

(**) Term: **15 Years**

(21) Appl. No.: **29/843,898**

(22) Filed: **Jun. 24, 2022**

(51) LOC (15) Cl. **23-03**

(52) U.S. Cl.

USPC **D23/413**

(57) **CLAIM**

The ornamental design for a ceiling fan blade, as shown and described.

DESCRIPTION

FIG. 1 is a bottom perspective view of a ceiling fan blade shown in the environment of a ceiling fan, showing the claimed design;

FIG. 2 is a bottom perspective view of the ceiling fan blade of FIG. 1, having the ceiling fan environment removed;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the ceiling fan blade and ceiling fan environment that form no part of the claimed design.

1 Claim, 8 Drawing Sheets
